UNITED STATES PATENT OFFICE

1,967,878

INCANDESCENT LAMP OR SIMILAR DEVICE

Walter J. Geiger, Cleveland Heights, and Alfred T. Gaskill, Cleveland, Ohio, assignors to General Electric Company, a corporation of New York

Application October 13, 1932, Serial No. 637,620

5 Claims. (Cl. 176—32)

Our invention relates to electric incandescent lamps and to other similar devices which are to be connected in some convenient manner to a source of electrical energy. More particularly, our invention relates to the base or terminal portion of such devices which, when fitted into an appropriate socket, completes the electric connection of the device. One object of our invention is to provide an extremely simple base which is both reliable and inexpensive. Another object of our invention is to provide a simple construction which allows the lamp or other device to be very conveniently inserted in a socket and removed therefrom. Other features and advantages of our invention will appear from the drawing and the description which follows of various species thereof.

Referring now to the drawing, Fig. 1 is a perspective view of an electric incandescent lamp comprising our invention; Fig. 2 is a vertical section therethrough and through a socket with the contact-making elements revolved so as to make them appear in the section; Fig. 3 is a perspective view of a socket; Figs. 4 and 5 are perspective and vertical sectional views respectively of a modified form of our invention; and Figs. 6 and 7 are corresponding views of another modification.

The specific embodiment of our invention shown in Figs. 1 and 2 comprises a bulb 10 with the neck portion 11, which is cylindrical in shape and which is preferably provided with a pair of longitudinal grooves 12 having protuberances 13 therein. The rim of the bulb is sealed to an outward extending flange 14 of stem 15 which is substantially perpendicular thereto, making a complete enclosure which is evacuated or gas filled as desired through tube 16. This so-called tipless construction is disclosed in Mitchell and White Patent No. 1,423,956. Electrical connection to the interior of the enclosure is made through leading-in wires 17 and 18, the inner ends of which are in this particular instance connected to respective ends of the filament 19. The outer ends of said wires pass through disc 20 at points preferably some distance from each other and at positions as near the flange 14 as possible. The disc 20 is an insulating member composed preferably of card board, hard rubber, asbestos or other similar and economical insulating sheet material and has a centrally located hole therein, through which the end of exhaust tube 16 protrudes and locates the disc correctly on flange 14 to which it may be glued or cemented. The ends of the leading-in wires 17, 18 extend through

apertures in the disc 20 and the extreme outer ends thereof may be fashioned as by coiling into terminal contacts 21. These terminals are preferably located on portions of disc 20 directly over flange 14 which prevents their dislocation when the lamp is pushed into a socket.

A suitable socket is shown in Figs. 2 and 3 and comprises spring fingers 22. These are positioned and shaped to engage the grooves 12 of the bulb neck and the protuberances 13 to hold the lamp securely with the terminal contacts 21 registering with the terminal fingers 24 of the socket. The lamp is prevented from improper insertion by the fact that the spring fingers 22 are backed up by stop screws 23 which prevent the sufficient separation of said fingers to receive the portions 11 other than the said grooves.

A modification of our invention is shown in Figs. 4 and 5. This lamp differs from that above described in that the exhaust tube 25 is sealed off within the hollow interior of the stem to lessen the chance of its becoming broken and the tubular portion 26 of the stem is also enlarged so this operation may be more easily performed. A modified form of base terminal is shown comprising globules of solder 27 each attached to an end of a leading-in wire.

In the modification of our invention shown in Figs. 6 and 7 the ends 28 of the leading-in wires are bent over on flange 14 to serve as terminals. 25 The open end of the stem is closed with an insulator 29 which serves to hold the terminals 28 in place as well as to insulate them. For this purpose, sealing wax may be melted, poured into the opening and allowed to harden.

What we claim as new and desire to secure by Letters Patent of the United States, is:

1. An electrical device consisting of a glass bulb and having a pair of lead wires sealed into and extending longitudinally from said bulb, terminals connected with said lead wires, and an insulating member firmly seated in the end of said bulb and serving to anchor said terminals, the adjacent end of said bulb being provided with a groove definitely located with reference to said terminals and adapted to be engaged by a corresponding socket member.

2. An electrical device consisting of a glass bulb and having a pair of lead wires sealed into and extending longitudinally from said bulb, terminals connected with said lead wires, and an insulating member firmly seated in the end of said bulb and serving to anchor said terminals, the adjacent end of said bulb being provided with a groove definitely located with reference to said

terminals and adapted to be engaged by a corresponding socket member, said groove having a transverse protuberance thereacross adapted to be engaged by said socket member to retain said device.

3. An electrical device consisting of a glass bulb having sealed therein a mount comprising a hollow stem having a flange at the end thereof and lead wires sealed in said stem and extending longitudinally thereof and an insulator separating the ends of said lead wires, the said lead wire ends being bent over on the said flange of said stem to constitute terminals.

4. An electrical device consisting of a glass bulb and having a pair of lead wires sealed into and extending longitudinally from said bulb, terminals connected with said lead wires, and an insulating

disc firmly seated in the end of said bulb and serving to anchor said terminals, the adjacent end of said bulb being provided with means for preventing improper insertion of the said device in a socket.

5. An electrical device consisting of a glass bulb and having a pair of lead wires sealed into and extending longitudinally from said bulb, terminals connected with said lead wires, and an insulating disc firmly seated in the end of said bulb and having openings therein through which said lead wires extend to said terminals which are anchored by said disc, the adjacent end of said bulb being provided with means for preventing improper insertion of the said device in a socket.

WALTER J. GEIGER.
ALFRED T. GASKILL.
